UNITED STATES PATENT OFFICE.

WILLIAM T. TRUAX, OF BATTLE CREEK, MICHIGAN, ASSIGNOR TO THE UNITED STATES REGISTER COMPANY, OF BATTLE CREEK, MICHIGAN, A CORPORATION OF MICHIGAN.

REGISTER-SLAT OPERATOR.

1,163,383.

Specification of Letters Patent. Patented Dec. 7, 1915.

Application filed February 16, 1915. Serial No. 8,520.

To all whom it may concern:

Be it known that I, WILLIAM T. TRUAX, a citizen of the United States, residing at Battle Creek, in the county of Calhoun and 5 State of Michigan, have invented certain new and useful Improvements in Register-Slat Operators, of which the following is a specification.

This invention relates to register slat operators, and belongs to the class of contrivances intended for use in connection with registers in ventilating and hot air heating 10 systems and apparatus.

The object of this invention is the production of a device for working the slats back 15 and forth, the whole including the slats being constructed of sheet metal, and the various parts having special formation and particular arrangement with regard one to 20 another, whereby manufacture is materially cheapened and a superior and very durable register is made.

The construction and arrangement of the 25 parts of this invention are illustrated in the accompanying drawings, of which—

Figure 1 represents a slat in its open position, the frame and slide being shown in section. Fig. 2 is a top plan view of the slat alone showing the ear formed at the top 30 thereof and the groove in the ear. Fig. 3 is a cross-section of the slat on the broken line $x-x$ of Fig. 1, looking in the direction of the arrow. Fig. 4 is a top plan view of the slat in its closed position with relation 35 to Fig. 1 or Fig. 7. Fig. 5 is a cross-section of the slide taken on the broken line $z-z$ of Fig. 7. Fig. 6 is a top plan view of the slat in its half closed position with relation 40 to Fig. 7. Fig. 7 is a horizontal section of a portion of the top of the register frame on the broken line $y-y$ of Fig. 1, showing a top plan view of a portion of the slide.

Throughout the drawings and description the same letter is used to refer to the same 45 part.

Considering the drawings, the slat A, made of sheet metal, has a stiffening groove a extending lengthwise. At the top and bottom, the reduced ends of the slat are 50 formed into hollow, cylindrical pintles or pivots B and b which engage suitable spaced holes in inwardly and forwardly turned portions C and c of the frame D of the register.

Lying transversely within the frame in 55 front of the pivots and on top of the slat is

a slide E, operated by a fingerpiece e. The slide is movable transversely with respect to the axis of the slat, and rests directly upon the ear F, that is formed by turning over an edge portion of the slat at right angles 60 with the plane of the slat. The ear F usually has the form shown in Figs. 2, 3, 4 and 6. The ear has an opening or upwardly-opening groove f. The axis of the groove is at an angle, ordinarily forty-five degrees, 65 with the plane of the slat, and the axis of the groove if extended would intersect perpendicularly the axis of the slat and the two axes would lie in one vertical plane.

As shown in Figs. 1, 2, and 4, the outer 70 ends of the grooves f are closed in order that when the parts are assembled as shown in Fig. 1, the tongues G may not slip out at the ends of the grooves.

As best illustrated in Fig. 5 the slide has 75 a tongue projecting downwardly below its bottom, made in practice by stamping out a piece of the bottom of the trough-like slide so that it is held by one end and extends downwardly. The tongue is designated by 80 the letter G and is constructed and arranged to engage the groove f when the parts are assembled as illustrated in Figs. 1 and 7. In Fig. 7 a second slat H is shown, and any desired number of slats may be employed. 85

In explaining the operation of this invention, let it be borne in mind that in Figs. 1 and 7 the slats are shown in their open positions. The open position of the slat alone is illustrated in Fig. 2. In Fig. 7 it will be 90 noted that the tongue G is near the outer end of the groove f. That is to say, when the slats are open the tongue is at the outer end of the groove. Suppose now movement is made to close the slats. Such a movement 95 would result from pressing the fingerpiece e in Fig. 7 toward the slat A. When half-way closed, each slat will assume the position illustrated in Fig. 6, and it will be understood that the groove f will then be arranged beneath the slide directly across it. Consequently the tongue G is no longer at the outer end of the groove f, but, by the movement of the groove and its own movement it now occupies a position intermediate 100 between the ends of the groove. The closing movement continuing, the groove takes its position again inclined or diagonally beneath the slide and the tongue and outer end of the groove are once more brought to 105 110

gether. The closed position of the slat is shown in Fig. 4. The movements opening the slats simply reverse the movements just described.

5 Having now explained the construction and operation of this invention, what I claim and desire to secure by Letters Patent of the United States is:—

In a register slat operator, the combination 10 with a sheet metal frame having the rear portions of its top and bottom turned inwardly and forwardly and provided with spaced holes, of slats having pivots at their ends engaging the said holes, each of the 15 said slats having a portion projecting horizontally from its top edge to form an ear, and the said ear having a groove extending

in a direction inclined to the plane of the slat and closed at its outer end, and an operating slide supported by the said ears and 20 provided with projecting tongues arranged to engage the grooves in the ears, the said slide being arranged against the front edge of the said inwardly and forwardly turned portion of the top of the frame, the said 25 front edge being a straight edge and constructed to guide the slide.

In testimony whereof I affix my signature in presence of two witnesses.

WILLIAM T. TRUAX.
